(57) CLAIM

The ornamental design for acupressure element for cupping device, as shown and described.

(22) Filed: **Oct. 21, 2010**

DESCRIPTION

(30) **Foreign Application Priority Data**

Apr. 21, 2010 (KR) 2010-17650

FIG. 1 is a top perspective view of the acupressure element for cupping device of my design;

(51) **LOC (9) Cl.** **24-04**

FIG. 2 is a front elevational view thereof, with the rear elevational view, left side elevational view and right side elevational view being the same;

(52) **U.S. Cl.** **D24/188**

FIG. 3 is a top plan view thereof;

(58) **Field of Classification Search** D24/188,

D24/200, 133, 142, 211, 214; 606/204, 201;

601/46, 62, 95, 107, 109, 134, 135, 169,

601/154, 157, 122, 121; 604/24, 189; D8/349;

368/10

FIG. 4 is a bottom plan view thereof;

See application file for complete search history.

FIG. 5 is an exploded, perspective view thereof;

(56) **References Cited**

FIG. 6 is a bottom perspective view thereof;

U.S. PATENT DOCUMENTS

FIG. 7 is a cross-sectional view thereof showing a state of attaching my design on an individual's skin in combination with a cupping device; and,

1,364,148 A * 1/1921 Springer 607/86
1,490,137 A * 4/1924 Springer 607/86
2,449,805 A * 9/1948 Develay et al. 601/8

FIG. 8 is a cross-sectional view thereof, taken along line 8-8 of FIG. 3.

The broken line showing of the cupping device and skin is included for the purpose of illustrating environmental structure and forms no part of the claimed design.
